Specification of Letters Patent. Patented May 10, 1921.

Application filed January 4, 1919. Serial No. 269,640.

To all whom it may concern:

Be it known that I, CHARLES S. DEMAREST, residing at Brooklyn, in the county of Kings and State of New York, have invented certain Improvements in Network-Selecting Circuits, of which the following is a specification.

This invention relates to repeater circuits and more particularly to repeater circuits equipped for the automatic selection of networks for balancing the lines with which the repeater may be associated.

In accordance with this invention, each end of a cord circuit repeater is provided with as many networks as may be necessary to balance the various types of transmission lines with which the repeater may be associated, and in addition several networks are provided for balancing various types of auxiliary apparatus, such as composite sets, which may be associated with some or all of the lines. Selecting relays are also provided, one for each network, the circuits of these relays being under the joint control of the line with which the repeater is associated and a series of controlling relays individual to the repeater. The repeater is also equipped with selecting circuits so arranged that when the two ends of the repeater are associated with transmission lines and the repeater controlling key actuated, all of the controlling relays associated with one end of the repeater are actuated to prepare the circuits of all of the selecting relays associated with that end of the repeater. A relay associated with the line at the same time completes the circuit for such selecting relays as are necessary to select the various networks for balancing the line and its associated auxiliary apparatus. Upon the energization of the proper selecting relays the corresponding networks are connected to one end of the repeater and the controlling relays are restored to normal and their circuits held open so that false operation of any other selecting relays is prevented. As soon as the networks have been selected for one end of the repeater the same operation is repeated for the other end.

During the process of selection and during the entire time that networks are being selected for the two ends of the repeater, a master relay, associated with the repeater, is energized. Selection cannot take place

unless this relay is energized and the circuits of the several master relays corresponding to each repeater are so arranged that when the master relay of any repeater is energized no other master relay can be actuated until the energized master relay is restored to normal, at the completion of the selection for the corresponding repeater. By means of this arrangement but one repeater may select networks at a time, thereby avoiding a possibility of false selection.

At certain times the composite sets, or other auxiliary apparatus associated with certain lines, are disconnected therefrom and it is therefore, desirable that when such apparatus is disconnected from any circuit the selection of a corresponding balancing network be prevented upon the association of a repeater with such circuit. Accordingly, arrangements are provided whereby when the composite sets are disconnected from the side circuits of a group of transmission lines, comprising the side and phantom conductors, simplex circuits are prepared for the side circuit and corresponding phantom, said simplex circuits including the talking conductors of the affected transmission lines. With the circuits in this condition, the association of a repeater with either a side circuit or a phantom circuit completes the corresponding simplex circuit and actuates means to hold open the circuits of the selecting relays of that repeater which control the selection of the auxiliary networks for balancing the composite sets.

One of the objects of the arrangement above described is to provide a network selecting arrangement such that false operation of the selecting devices will be reduced to a minimum. Another object is to provide a means whereby selection by more than one repeater at a time is prevented in a positive manner. Still another object of the invention is the provision of means for preventing the selection of networks for balancing auxiliary equipment when the corresponding auxiliary equipment has been removed from the line, said means being controlled over the talking circuit instead of over the sleeve circuit as has been the practice heretofore.

These features, as well as other objects of the invention will be clear from the fol-

lowing description of the invention when read in connection with the accompanying drawings, Figures 1, 2 and 3 of which, when placed end to end, constitute a circuit diagram of a preferred embodiment of the invention.

Referring to the drawings, a cord circuit repeater R, comprising amplifiers A₁ and A₂, terminates in plugs P₁ and P₂, adapted 10 to be inserted in jacks, such as J₁, J₂ and so forth, of transmission lines, such as L₁, L₂ and so forth. Transmission lines L₁, L₂ and L₃ constitute a group of which the lines L₁ and L₃ are side circuits while the line L₂ is 15 the corresponding phantom circuit. Lines L₄, L₅ and L₆ are similarly related. Each of the lines L₁, L₃, L₄ and L₆ is provided with a composite set for telegraphic purposes, the sets of the several lines being 20 symbolically represented at X₁, X₃, X₄ and X₆, respectively.

The left hand end of the repeater R is provided with a plurality of networks normally disconnected therefrom, the network 25 LN₁ being adapted to balance the lines L₁ or L₃ and the network PN₁ being adapted to balance the phantom line L₂. The network XN₁ is adapted to balance the composite sets X₁ and X₃, associated with the lines L₁ and L₃, while another 30 network XN₁' is adapted to balance the composite sets X₁ and X₃ with respect to the phantom line L₂. Additional networks may be provided for as many other types of 35 lines and auxiliary apparatus as may be present in the system. In a similar manner, the right hand end of the repeater is provided with networks LN₂, PN₂, XN₂ and XN₂', and so forth. Selecting relays for 40 controlling the connection of the proper network or networks to each end of the repeater upon its association with the transmission line are provided, as will more fully appear hereinafter.

In order that the composite set X₁ may 45 be removed from the transmission line L₁ twin jacks J₁₀ and J₁₁ are provided, these jacks being so arranged that when twin plugs P₁₀ and P₁₁ are inserted therein the composite set X₁ is disconnected from the 50 line and a direct connection is established in its place. Similar arrangements are provided for removing the composite sets X₃, X₄ and X₆. When the composite set is 55 moved from a line it is desirable that means be provided to prevent the repeater from selecting a network for balancing the composite set. Accordingly, a simplex circuit is associated with the talking conductors of 60 each transmission line, which is adapted to be closed at one point by the insertion of a twin plug in the corresponding twin jack for removing the composite set. When the repeater is associated with the line the simplex circuit is completed through a relay 65

which opens the circuits of the selecting relays which control the networks for balancing the composite sets. The phantom line corresponding to the side circuit from which the composite set has been removed is also 70 provided with a similar simplex circuit which is prepared at the same time that the composite sets are removed from the side circuits.

A master relay MR is provided for the 75 repeater R and similar master relays MR', MR'', and so forth, are provided for other repeaters. In order that a repeater, such as R, may select networks, the corresponding master relay MR must be energized and remain energized until the networks are selected for both ends of the repeater. The circuits of these master relays are so arranged that when the master relay of one repeater is energized no other master relay 80 can be operated until the master relay which is energized is restored to normal at the end of a process of selecting networks. Consequently, but one repeater may select networks at any given instant. 90

It is believed that the invention is of such a nature that further details of the apparatus may be best understood from a description of the operation thereof, which is as follows: Assuming that it is desired to 95 connect the side circuit transmission line L₁ with the phantom transmission line L₅ through the repeater R, the repeater operator inserts the plug P₁ in the jack J₁ of the line L₁ and the plug P₂ in the jack J₅ of 100 the line L₅. As a result of these operations, sleeve circuits are completed as follows: from battery, through sleeve relay 1, over the sleeve contacts of plug P₁ and jack J₁, through the windings of sleeve relay 2 and 105 marginal relay 3, associated with the line L₁, to ground. Relays 1 and 2 are energized over this circuit but the relay 3 being marginal, does not attract its armature. Relay 2 disconnects battery from the winding of 110 relay 4 which is connected through equal resistances to a simplex circuit extending over the talking conductors of the line L₁. A circuit is also completed from battery through the winding of sleeve relay 5, sleeve 115 contacts of plug P₂ and jack J₅ and through the windings of sleeve relay 6 and marginal relay 7 associated with the line J₅. Relays 5 and 6 are energized but the relay 7, like relay 3, is marginal and does not attract its 120 armature. Relay 6 disconnects battery normally connected to the midpoints of the resistances bridged across the conductors of the phantom line L₅.

The operator now actuates the repeater 125 controlling key K, thereby completing a circuit from battery, over the lower normal contact of relay 8, front contacts of relays 1 and 5, make contact of key K, lower normal contact of relay 9, through the winding 130

of master relay MR and thence in series over the extreme right hand back contacts of succeeding master relays MR', MR'', and so forth, of other repeaters, to ground. It 5 will be seen that since this circuit passes through the contacts of all the master relays of the other repeaters, the relay MR cannot be energized if any other master relay is actuated. Consequently, if at the 10 time the repeater controlling key K was actuated the master relay of another repeater was energized, the circuit above described would not be completed until the master relay of the other repeater is restored to normal, which does not occur until the completion 15 of the selecting operation for the other repeater. Assuming, however, that no other master relay is actuated, the master relay MR is energized over the circuit above traced and upon attracting its right hand armature opens the energizing circuit of all 20 of the other master relays, such as MR' and MR'', which, it will be noted, pass over the right hand back contact of the relay MR. 25 The energization of master relay MR also completes the following circuit; from battery, over the right hand front contact of relay MR, back contact of relay 10, left hand front contact of relay MR, through 30 the winding of sleeve relay 1 and over the sleeve circuit previously traced through the marginal relay 3 to ground. The current over the sleeve circuit is now sufficiently increased to energize marginal relay 3 which 35 attracts its armatures, with a result to be presently stated. At the same time that the above circuit was completed an additional circuit was established from battery, over the right hand front contact of relay MR, 40 upper back contact of relay 8, over conductor 11, and thence in parallel through the windings of controlling relays 12, 13, and so forth, to ground. Battery is also connected over the front right hand contact of relay 45 MR and upper back contact of relay 8, through the winding of relay 14 to conductor 15, so that when the controlling relays 12, 13, and so forth, are energized battery is applied over the front contacts of said 50 controlling relays to all of the selecting relays, such as 16, 17, 18, 19, and so forth, associated with the left end of the repeater. Consequently, when marginal relay 3 attracted its armatures a circuit was completed 55 as follows: from ground, over the lower front contact of relay 3, upper normal contact of selecting relay 16, through the winding and over the lower normal contact of said relay and over the left hand 60 front contact of relay 13 to battery connected to conductor 15. At the same time an additional circuit was completed from ground, over the upper front contact of marginal relay 3, over the upper normal 65 contact of selecting relay 18, through the winding and over the lower normal contact of said relay and over the left hand front contact of controlling relay 12 to battery connected to conductor 15. Since battery is applied to the circuits above traced over the conductor 15, through the winding of relay 14, said relay 14 is energized and at its lower front contact short circuits the winding of relay 10. 70 Selecting relays 16 and 18 are energized over the circuits above traced and are locked up independently of marginal relay 3 and controlling relays 12 and 13 over a circuit from battery, right hand front contact of relay MR, lower front contact of relay 14, 75 through resistance 20, conductor 21, and thence in parallel over the lower front contacts of relays 16 and 18, through the windings of said relays and over the upper front contacts of said relays to ground. As soon as all of the selecting relays controlled by the marginal relay of the line are energized and locked up, (in this case relays 16 and 18), the circuits traced through the winding of relay 14 are all opened so that said relay 80 is deenergized and opens a short circuit about the winding of relay 10. The locking circuits just traced for the selecting relays now extend from resistance 20 to battery through the winding of relay 10 and over 85 the front right hand contact of relay MR. Relay 10 is accordingly energized and upon attracting its armature opens the direct battery connection hereinbefore traced, over the left hand front contact of relay MR to the 90 sleeve circuit, so that the current flow over the sleeve circuit is reduced sufficiently to cause the deenergization of marginal relay 3 and the consequent opening of the initial 95 energizing circuits of relays 16 and 18. Relay 16 functions to connect the balancing network LN₁ to the balancing circuit 22 associated with the left end of the repeater R for the purpose of balancing the transmission line L₁. Selecting relay 18 at its upper 100 front contact completes a circuit from battery through the winding of relay 23, over the back contact of relay 24 and through the winding of relay 25 to ground. Relay 25 disconnects the two sections of balancing 105 circuit 22, while the relay 23 connects the balancing network XN₁ between the two sections for the purpose of balancing the composite set X₁. 110 If the composite set X₁ had been removed from the line L₁, by inserting plugs P₁₀ and P₁₁ in the jacks J₁₀ and J₁₁, a simplex circuit would have been completed as follows: from ground, over the sleeve contacts of the plugs and jacks just mentioned, through the 115 winding of relay 4, and thence in parallel through resistances 26 and 27 over the tip and ring contacts of the jacks J₁ and plug P₁, through resistances 28 and 29 in parallel and thence through the winding of relay 24 120 125 130

to battery. Relay 24 is energized over the simplex circuit above traced and upon attracting its armature holds open the circuit previously traced through the windings of 5 relays 23 and 25. Consequently, these relays will not be operated and the network XN_1 will not be interpolated in the balancing circuit 22. The energization of relay 4 upon the completion of the simplex circuit connects 10 ground to the midpoint of the simplex resistance connected across the phantom line L_2 , so that upon the connection of a repeater with the phantom line the relay of said repeater corresponding to relay 24 15 will be energized to prevent the selection of the phantom composite balancing network, as will more clearly appear hereinafter.

Returning to the relay 10, the energization of said relay in addition to causing 20 circuit changes already described, results in the completion of a circuit from battery, over the front right hand contact of relay MR, over the front contact of relay 10 and through the winding of relay 8 to ground. 25 Relay 8 upon being energized, by opening its upper back contact breaks the circuit of the controlling relays 12 and 13 and at its lower front contact establishes a new holding circuit for the relay MR, from 30 battery, over the lower front contact of relay 8, front contacts of relays 1 and 5, lower back contact of relay 9, through the winding of relay MR to ground over a circuit previously traced. Over the middle front contact of relay 8 a circuit is completed from 35 battery, front right hand contact of relay MR, middle front contact of relay 8, back contact of relay 30, through the winding of sleeve relay 5, to ground, over a circuit previously traced through the marginal relay 7. Since battery is thus directly applied 40 to the sleeve circuit, the current flow there-over is increased sufficiently to energize marginal relay 7, with results hereinafter 45 stated.

At the same time that the circuit above traced for marginal relay 7 was completed an additional circuit was established as follows: from battery, over the right hand 50 front contact of relay MR, upper front contact of relay 8, upper back contact of relay 9 and over conductor 31 and through the windings of controlling relays 32, 33, and so forth, to ground. Battery is at the 55 same time connected through the winding of relay 34 to conductor 35, so that upon the energization of the various controlling relays, such as 32 and 33, circuits are prepared over the front contacts of said controlling relays for the various selecting relays, such as 36, 37, 38, 39, and so forth. Consequently, the energization of marginal relay 7 results in the completion of a circuit from ground, over the lower front contact of said marginal relay, over the upper

back contact of selecting relay 37, through the winding and over the inner lower back contact of said relay, over the left hand front contact of relay 33, over the conductor 35, through the winding of relay 34 and 70 thence over a circuit previously traced to battery. A similar circuit is also completed for selecting relay 39, from ground, over the upper front contact of marginal relay 7, middle back contact of relay 39, through 75 the winding and over the lower back contact of said relay and over the left hand front contact of relay 32, over conductor 35 to battery through the winding of relay 34.

Relay 34 is energized over the circuits 80 above traced and maintains the winding of relay 30 shorted circuited. Relays 39 and 37 upon being energized establish locking circuits from ground, over their front contacts and over conductor 40, through resistance 41, over the lower front contact of relay 34 and thence to battery over a circuit already traced through the upper front contact of relay 8. As soon as all of 85 the selecting circuits whose initial energization circuits were completed have been energized and locked up the relay 34 is de-energized and opens a short circuit about the winding of the relay 30 which is now included in the locking circuit of the selecting relays, through resistance 41 and over conductor 40. Relay 30 upon being energized opens the direct battery connection to the sleeve circuit so that the current flow over said circuit is reduced and the marginal relay 7 is de-energized, thereby opening the initial energizing circuits of the selecting relays 39 and 37. At its front contact 90 relay 30 completes a circuit for relay 9 as follows: from battery, over the right hand front contact of relay MR, middle front contact of relay 8, front contact of relay 30 and through the winding of relay 9 to ground. 95

Relay 9 upon being energized opens a 100 battery connection which was traced over its upper back contact to conductors 31 and 35, so that the controlling relays 32, 33, and so forth, are restored to normal. By opening its lower back contact said relay opens 105 a circuit previously traced for the master relay MR, which is restored to normal. Holding circuits for relays 8, 10, 9, and 30 are at the same time established over the lower front contact of relay 9 independent 110 of the relay MR as follows: from battery, over the lower front contact of relay 8, front contact of relays 1 and 5, make contact of repeater controlling key K, lower front contact of relay 9 to point 42, from which one 115 branch extends over the lower front contact of relay 10 and through the winding of relay 8 to ground. Another branch extends from point 42, through the winding of relay 10 and through the resistance 20, 120

125 130

over conductor 21 and through the locking circuits of the selecting relays 16 and 18 to ground. An additional path extends from point 42 over the upper front contact of relay 8, through the winding of relay 30, through resistance 41, over conductor 40 and over the locking circuits previously traced for relays 39 and 37 to ground. Still another path extends from point 42, over the middle front contact of relay 8, lower front contact of relay 30 and through the winding of relay 9 to ground. Relays 8, 10, 9 and 30 as well as the various selecting relays will, therefore, remain energized so long as the repeater control key K remains actuated and the sleeve relays 1 and 5 are energized.

Returning now to the selecting relays 37 and 39, which are locked up over circuits previously traced, it will be noted that the relay 37 functions to connect the network PN_2 to the balancing circuit 43 at the right end of the repeater in order to balance the phantom line L_5 . The selecting relay 39, at its upper front contact completes a circuit from battery, through the winding of relay 44, over the upper front contact of relay 39, over the lower back contact of relay 45, through the winding of relay 46 to ground. Relay 46 opens the two sections of the balancing circuit 43, while relay 44 connects the phantom composite network XN_2' between the two sections for the purpose of balancing the effect of the composite sets X_4 and X_6 with respect to the phantom line L_5 .

In case the composite sets X_4 and X_6 has been removed from the side circuits L_4 and L_6 by inserting plugs P_{14} , P_{15} , P_{16} and P_{17} in jacks J_{14} , J_{15} , J_{16} and J_{17} , respectively, the following circuit would have been completed: from ground, over the sleeve contacts of jack J_{14} and plug P_{14} , in parallel with the sleeve contacts of jack J_{15} and plug P_{15} , through the winding of relay 46 and over the back contact of relay 47 to battery. A circuit would also be completed from ground, over the sleeve contacts of jack J_{16} and plug P_{16} in parallel with the sleeve contacts of jack J_{17} and plug P_{17} , through the winding of relay 48 and over the back contact of relay 49 to battery. The energization of relays 46 and 48 over the circuits above traced results in the connection of ground over the front contact of said relays to the midpoints of resistances 50 and 51 bridged across the talking conductors of the phantom line L_5 . Consequently, the insertion of the plug P_2 of the repeater R in the jack J_5 of the phantom line L_5 would result in completing a circuit from battery, through the winding of relay 45 to the midpoints of resistances 52 and 53 and thence in parallel through said resistances over the tip and ring contacts of plug P_2 and jack J_5 , in parallel

through resistances 50 and 51 to ground, over the front contacts of relays 46 and 48. Relay 45 upon being energized would hold open the circuit of relays 46 and 39 so that the phantom composite balancing network XN_2' would not be interpolated in the balancing circuit 43.

The apparatus will be returned to normal either by restoring the key K or by withdrawing the plugs P_1 and P_2 with the consequent deenergization of the sleeve relays 1 and 5. This follows from the fact that battery was supplied over the contacts of relays 1 and 5 and the contact of the key K for locking up relays 8, 10, 9 and 30, as well as the operated selecting relays 16, 18, 37 and 39.

The arrangements above described provide a simple and efficient circuit arrangement for selecting repeater networks with minimum possibility of false selection and also afford suitable means for automatically determining whether or not the balancing arrangement for the composite sets shall be included in the balancing circuit. While the invention has been shown as incorporated in a certain circuit arrangement, it will be obvious that the general principles herein disclosed may be embodied in many other organizations widely different from those illustrated without departing from the spirit of the invention as defined in the following claims.

What is claimed is:

1. In a signaling system, a plurality of lines of different types, repeaters for interconnecting said lines, balancing networks for each type of line, a plurality of selecting relays for each repeater, controlling relays for said selecting relays associated with each repeater, means responsive to the association of a repeater with a line to cause said controlling relays of that repeater to prepare circuits for all of the selecting relays of that repeater, means determined by the line with which the repeater is associated for completing a circuit for a selecting relay corresponding to that type of line only, and means responsive to the actuation of said selecting relay to associate a balancing network with the repeater and to hold open the circuits of said controlling relays.

2. In a signaling system, a plurality of lines of different types, repeaters for interconnecting said lines, balancing networks for each type of line, a plurality of selecting relays for each repeater, controlling relays for said selecting relays associated with each repeater, means responsive to the association of a repeater with a line to cause said controlling relays of that repeater to prepare circuits for all of the selecting relays of that repeater, means determined by the line with which the repeater is associated for completing a circuit for a selecting relay corre-

sponding to that type of line only, means responsive to the actuation of said selecting relay to associate a balancing network with the repeater and to lock up said selecting relay, and means responsive to the locking up of said selecting relay to open and hold open the circuits of said controlling relays.

3. In a signaling system, a plurality of lines of different types, repeaters for interconnecting said lines, balancing networks for each type of line for each end of said repeaters, a plurality of selecting relays for each end of each repeater, sets of controlling relays for said selecting relays associated with each end of each repeater, means responsive to the association of the two ends of a repeater with lines to be connected through the repeater to cause the controlling relays associated with one end of the repeater to prepare selecting circuits for all the selecting relays associated with that end of the repeater, means determined by the line with which that end of the repeater is connected for completing a circuit for a selecting relay corresponding to that type of line only, means responsive to the actuation of said selecting relay to associate a balancing network with that end of the repeater, to hold open the circuits of the controlling relays associated with that end of the repeater, and to cause the controlling relays associated with the other end of the repeater to prepare circuits for all of the selecting relays associated with the other end of the repeater, means controlled by the line with which the other end of the repeater is associated for completing a circuit for a selecting relay associated with that end of the repeater and corresponding to that type of line only, and means responsive to the actuation of said selecting relay to associate a balancing network with the other end of the repeater and to hold open the circuits of the controlling relays associated with the other end of the repeater.

4. In a signaling system, a plurality of lines of different types, repeaters for interconnecting said lines, balancing networks for each type of line for each end of said repeaters, a plurality of selecting relays for each end of each repeater, sets of controlling relays for said selecting relays associated with each end of each repeater, means responsive to the association of the two ends of a repeater with lines to be connected through the repeater to cause the controlling relays associated with one end of the repeater to prepare selecting circuits for all the selecting relays associated with that end of the repeater, means determined by the line with which that end of the repeater is connected for completing a circuit for a selecting relay corresponding to that type of line only, means responsive to the actuation of said selecting relay to associate a balanc-

ing network with that end of the repeater and to lock up said selecting relay, means responsive to the locking up of said selecting relay to open and hold open the circuits of the controlling relays associated with that end of the repeater and to cause the controlling relays associated with the other end of the repeater to prepare circuits for all of the selecting relays associated with the other end of the repeater, means controlled by the line with which the other end of the repeater is associated for completing a circuit for a selecting relay associated with that end of the repeater and corresponding to that type of line only, means responsive to the actuation of said selecting relay to associate a balancing network with the other end of the repeater and to lock up said selecting relay, and means responsive to the locking up of said selecting relay to open and hold open the circuits of the controlling relay associated with the other end of the repeater.

5. In a signaling system, transmission lines, auxiliary apparatus associated with said transmission lines, a repeater, networks for balancing said transmission lines and said auxiliary apparatus, means whereby when said repeater is associated with a transmission line a network is selected to balance said line, and another network is selected to balance said auxiliary apparatus, and means controllable over the talking conductors of said transmission line to defeat the selections of the latter network.

6. In a signaling system, transmission lines, auxiliary apparatus associated with said transmission lines, a repeater, networks for balancing said transmission lines and said auxiliary apparatus, means whereby when said repeater is associated with a transmission line a network is selected to balance said line, and another network is selected to balance said auxiliary apparatus and means controllable over a simplex circuit including the talking conductors of said transmission line to defeat the selection of the latter network.

7. In a signaling system, transmission lines, auxiliary apparatus associated with certain of said transmission lines, a repeater, networks for balancing said transmission lines and said auxiliary apparatus, means whereby when said repeater is associated with a transmission line including auxiliary apparatus, networks are selected for balancing said line and auxiliary apparatus, and means controllable over the talking conductors of the transmission line for defeating the selection of a network for balancing the auxiliary apparatus when said repeater is associated with a line having no auxiliary apparatus.

8. In a signaling system, transmission lines, auxiliary apparatus associated with certain of said transmission lines, repeater

networks for balancing said transmission lines and said auxiliary apparatus, means whereby when said repeater is associated with a transmission line including auxiliary apparatus, networks are selected for balancing said line and auxiliary apparatus, and means controllable over a simplex circuit including the talking conductors of the transmission lines for defeating the selection of a network for balancing the auxiliary apparatus when said repeater is associated with a line having no auxiliary apparatus.

9. In a signaling system, transmission lines, auxiliary apparatus associated with said transmission lines, a repeater, networks for balancing said transmission lines and said auxiliary apparatus, means whereby when said repeater is associated with a transmission line a network is selected to balance said line, and another network is selected to balance said auxiliary apparatus and means responsive to the disconnection of the auxiliary apparatus from a transmission line to prepare a simplex circuit over the talking conductors of said line, whereby the selection of a network to balance the auxiliary apparatus may be de-

feated when a repeater is associated with the line.

10. In a signaling system, a pair of transmission lines comprising side circuit conductors, a phantom transmission line including the side circuit conductors of the two transmission lines, auxiliary apparatus associated with the conductors of each side circuit, a repeater, a plurality of networks for balancing said side circuits, phantom circuit and auxiliary apparatus, means whereby when the repeater is associated with any one of said lines networks are selected to balance the line and the auxiliary apparatus associated with its conductors, and means responsive to the disconnection of the auxiliary apparatus from the side circuit conductors to prepare simplex circuits over the talking conductors of the side circuit and the phantom whereby the selection of a balancing network for the auxiliary apparatus will be prevented when the repeater is associated with either the side circuit or the phantom.

In testimony whereof I have signed my name to this specification this thirtieth day of December, 1918.

CHARLES S. DEMAREST.
